DESIGN FOR A HEAT DISPERSING DEVICE TO AID IN COOKING

John A. Breen, Pasadena, Calif.

Application November 22, 1943, Serial No. 111,756

Term of patent 7 years

(Cl. D81—26)

To all whom it may concern:

Be it known that I, John A. Breen, a citizen of the United States of America and a resident of Pasadena, in the county of Los Angeles, State of California, have invented a new, original, and ornamental Design for a Heat Dispersing Device to Aid in Cooking, of which the following is a specification, reference being had to the accompanying drawing, forming a part thereof.

In the drawing:

Figure 1 is a plan view of a heat dispersing device to aid in cooking, showing my new design. The opposite side not shown is substantially plain; and,

Figure 2 is a side view of the device shown in Figure 1.

I claim:

The ornamental design for a heat dispersing device to aid in cooking, as shown and described.

JOHN A. BREEN.
